VENTILATOR

Hugh Hill, Anderson, Ind.

Application June 22, 1940, Serial No. 341,789

9 Claims. (Cl. 230—45)

This invention relates to a device which with an associated fan is adapted for use to move air, especially for exhaust purposes or for circulating.

In the operation of a fan in free air, the blast of air immediately ahead of the fan is in the form of a hollow cylinder, and the air which passes through the fan is but a small proportion of the total amount of air moved. The blast of air which passes through the fan draws in air from the sides of such blast and moves that air. When such a fan is used for exhaust purposes, it is normally mounted in an opening not much larger than the fan diameter with the fan close to the plane of the wall through which the opening extends. This arrangement materially reduces the possible efficiency of the fan because it prevents the blast of air from drawing in and exhausting any air except substantially that which passes through the fan itself.

It is the object of my invention to provide a device which will efficiently take advantage of the tendency of a blast of air from the fan to draw in and move air which lies at the sides of the blast. It is my object to secure the exhaust movement of a large volume of air efficiently and quietly with a relatively small fan.

In accomplishing the objects of my invention I mount a fan in position so that its blast is received by a large end of a frusto-conical nozzle which has a discharge small end smaller than the fan diameter, so that the air blast is compressed and made more uniform over its whole area. This nozzle discharges through a gas passage of gradually increasing cross sectional area and formed as a series of venturis, with a large inlet opening at each of the venturis through which the blast of air from the fan induces air flow.

The accompanying drawing illustrates my invention. In such drawing, Fig. 1 is a vertical section of an exhaust device embodying my invention; and Fig. 2 is an end elevation of the device shown in Fig. 1.

The device shown in the drawing comprises a ring 10 adapted to be mounted in an outlet opening in a wall 11. Circumferentially spaced frame members 12 are supported on a ring 10 and extend rearwardly therefrom to a smaller ring 13 at their rear ends. A fan 14 and its motor 15 are mounted in position immediately behind the ring 13 so that the fan 14 will discharge through such ring 13. The inner diameter of the ring 13 is slightly larger than the fan diameter. Desirably, a frusto-conical casing 16 is supported by the ring 13 around the fan 14 to form an air

inlet passage thereto. A frusto-conical nozzle 17 is carried at its large rear end by the ring 13 and extends forwardly therefrom. Its forward and smaller end provides a discharge opening having a diameter approximately three-quarters the fan diameter. The conical walls of the nozzle 17 have an inclined angle of approximately 30°. Forwardly of the nozzle 17 there are a series of nested frusto cones 18. The walls of each has an included angle the same as that of the nozzle 17, and their inner and smaller ends lie on the surface of an imaginary cone having an apical angle of 10°. The exhaust end of the nozzle 17 also lies on this surface. Desirably, the walls of the frusto cones 18 have a length equal to approximately three-quarters of the fan diameter, and the cones are spaced in their nested relationship so that each overlaps its preceding one approximately a quarter of its wall-length. At the small end of each frusto cone 18 there is a flange 19 which flares outwardly from the surface of the imaginary 10° cone at an angle of the order of 15°.

Each frusto cone 18 is suitably supported at the frame member 12. In the drawing I have shown the frame members 12 as inwardly open channels and the mounting for the frusto cones 18 as fingers 20 extending between the legs of the channels and suitably secured as by riveting to the webs of the channels.

In this structure, the fan 14 discharges a blast of air through the ring 13 and into the compressing nozzle 17, in which the cylindrical character of the blast is substantially eliminated so that the air issues from the nozzle 17 at a more uniform rate over its whole cross-sectional area. As the air travels through the passage within the imaginary cone, it reacts at each of the flanged ends of the frusto cones 18 to set up an ejector action which causes a flow of air inwardly through the passages between the nested frusto cones 18 to increase the volume of air passing through the gas passage. This action is repeated at each of the frusto cones 18 so that the volume of air exhausted is much greater than that which issues from the nozzle 17.

The device is of simple construction, it greatly increases the capacity of a small fan, and moves and exhausts a large volume of air in proportion to the size of the fan. It is much more quiet in operation and less expensive to operate than would be a fan which when mounted at the exhaust opening will be sufficient to move an equivalent quantity of air.

My exhaust device is especially adapted for

use in exhausting air which carries dust particles or paint, as from a spray booth or sand-blast room, for it can be mounted with its rear end connected to the rear wall 21 of such a spray booth so that the air which passes through the fan 14 and past the motor 15 is free from such dust or paint particles, while the dust or paint-laden air is exhausted by being drawn between the frusto cone 18 into the blast of clean air from the fan 14.

I claim as my invention:

1. An exhaust device, comprising a fan, a frusto-conical nozzle disposed with its large end in position to receive the blast of the fan and having a small end smaller than the diameter of the fan, a series of frusto-conical members of similar apical angle associated with said nozzle, said members being of progressively increasing diameter along the series toward the exhaust end thereof, disposed with their small ends toward such exhaust end, and being axially spaced less than the axial lengths of the members, whereby the small ends of the members lie on the surface of an imaginary cone, and a flange at the small end of each of said members extending toward the exhaust end of the series and flared outwardly away from the surface of said imaginary cone.

2. An exhaust device, comprising a primary gas-mover, a nozzle through which said gas-mover discharges, a series of frusto-conical members of similar apical angle associated with said nozzle, said members being of progressively increasing diameter along the series toward the exhaust end thereof, disposed with their small ends toward such exhaust end, and being axially spaced less than the axial lengths of the members, whereby the small ends of the members lie on the surface of our imaginary cone, and a flange at the small end of each of said members extending toward the exhaust end of the series and flared outwardly away from the surface of said imaginary cone.

3. An exhaust device, comprising a fan, a frusto-conical nozzle disposed with its large end in position to receive the blast from the fan and having a small end approximately three-fourths the diameter of the fan, a series of frusto-conical members associated with said nozzle, said members each having an apical angle of approximately 30° and a wall length approximately three-fourths the diameter of the fan, said members being disposed with their small ends toward the exhaust end of the series and axially spaced from each other and being or progressively increasing diameter along the series whereby their small ends lie on the surface of an imaginary cone with an apical angle of approximately 10°, and a flange at the small end of each member extending toward the exhaust end of the series and flared outwardly away from the surface of said imaginary cone.

4. An exhaust device, comprising a fan, a frusto-conical nozzle disposed with its large end in position to receive the blast from the fan and having a small end approximately three-fourths the diameter of the fan, a series of frusto-conical members associated with said nozzle, said members each having an apical angle of approximately 30° and a wall length approximately three-fourths the diameter of the fan, said members being disposed with their small ends toward the exhaust end of the series and axially spaced from each other and being of progressively in-

creasing diameter along the series whereby their small ends lie on the surface of an imaginary cone with an apical angle of approximately 10°.

5. An exhaust device, comprising a fan, a nozzle positioned to receive the blast of the fan and to reduce the diameter of such blast, means forming a co-axial series of venturis and defining an unobstructed gas passage therethrough arranged to receive the blast from said nozzle and convey it to a discharge point, said venturis being of increasing cross-sectional area toward the discharge end of said passage, and inlets communicating with said passage at each said venturi and opening into the said passage at a small angle with respect to the axis thereof, through which inlets gas enters and is entrained by the flow of said blast through said series of venturis.

6. An exhaust device, comprising a primary gas-mover, means forming an open gas-passage through which said gas mover discharges and leading to an exhaust point, said passage-forming means including a series of spaced walls inclined at a small angle with respect to and toward said gas passage and forming inlet passages between them, said walls being successively farther from the axis of said passage in the direction of flow therethrough whereby said gas-passage is of increasing cross-sectional area toward said exhaust end and gas is drawn through said inlet passages and entrained by the flow of said blast through the open gas-passage, and flanges on said walls at the inner ends thereof inclined away from the axis of said gas-passage to increase the cross-sectional areas defined by said flanges at a greater rate than that of the open gas-passage.

7. The combination defined in claim 6 in which the primary gas mover is arranged to receive gas from one source and the said inlet passages receive gas from a second separate source.

8. An exhaust device, comprising a fan, a frusto-conical nozzle positioned to receive the blast from said fan, the small end of the nozzle being smaller than the fan diameter and arranged to discharge into an open gas passage leading to an exhaust point, said gas passage being formed of means including a series of spaced walls inclined at a small angle with respect to and toward said gas passage and forming inlet passages between them, said walls being successively farther from the axis of said passage in the direction of flow therethrough whereby said gas-passage is of increasing cross-sectional area toward said exhaust end and gas is drawn through said inlet passages and entrained by the flow of said blast through the open gas-passage, and flanges on said walls at the inner ends thereof inclined away from said gas passage.

9. An exhaust device, comprising a fan, a frusto-conical nozzle receiving the blast from said fan and having a discharge small end of approximately three-fourths the fan diameter, a gas-passage into which said nozzle discharges, and formed by a co-axial series of frusto-cones of similar apical angle of the order of 30° and disposed with their small ends in the direction of flow and on the surface of an imaginary cone with an apical angle of the order of 10°, said nozzle small end also lying on said surface, and flanges at the small ends of said frusto cones flaring outwardly from said imaginary cone.

CERTIFICATE OF CORRECTION.

Patent No. 2,306,727.

December 29, 1942.

HUGH HILL.

It is hereby certified that error appears in the printed specification of the above numbered patent requiring correction as follows: Page 1, second column, line 7, for "inclined" read --included--; page 2, first column, line 54, claim 3, for "being or" read --being of--; and that the said Letters Patent should be read with this correction therein that the same may conform to the record of the case in the Patent Office.

Signed and sealed this 16th day of February, A. D. 1943.

Henry Van Arsdale,
